FIG. 1

FIG. 2

FIG. 3

FIG. 4

FIG. 5

FIG. 8

FIG. 7

FIG. 6

FIG. 1 is a left side elevation of a hand-held high speed dental handpiece, showing my new design;

FIG. 2 is a bottom plan view of the handpiece of FIG. 1, showing the bur-receiving portion of the handpiece;

FIG. 3 is a right side elevation of the hand-held high speed dental handpiece of FIG. 1;

FIG. 4 is a top plan view thereof;

FIG. 5 is a front end elevation thereof;

FIG. 6 is a rear end elevation thereof as seen from the right-hand end of FIG. 3;

FIG. 7 is a sectional view of the handpiece of FIG. 4 as seen on the line 7—7 thereof; and

FIG. 8 is a sectional view of the handpiece of FIG. 4 as seen on the line 8—8 thereof.

The characteristic feature of my design resides in the specific configuration of the triangular portions of the handle member as best illustrated in the cross-sectional views shown in the drawing.

I claim:

The ornamental design for a hand-held high speed dental handpiece, as shown and described.
